TYPE-WRITING MACHINE.

1,018,701.

Specification of Letters Patent.

Patented Feb. 27, 1912.

Application filed June 1, 1909. Serial No. 499,375.

To all whom it may concern:

Be it known that I, WILLIAM ALLAN DYER, a citizen of the United States, and resident of Syracuse, in the county of Onondaga and State of New York, have invented certain new and useful Improvements in Type-Writing Machines, of which the following is a specification.

My invention relates especially to paper feeding mechanism for typewriting machines and has for its object to provide improved devices of the class specified.

More specifically my invention resides in an improved paper finger contrivance.

As heretofore constructed paper fingers have been mounted to slide bodily lengthwise of the platen and have also been adapted to be moved to a limited extent transversely of the platen toward and away from the surface of the platen or the paper thereon. In some instances, for example where manifold work is being done and the paper fingers are coöperating with at least two sheets of paper and a carbon inlay, it has usually been the custom when making erasures to turn the platen forward by hand, thereby advancing the paper until the line to be corrected has been fed forward out of the control of the paper fingers. This enables the outer sheet and the carbon to be turned back from the platen, uncovering the inner sheet so that the same may be corrected, an operation which was impossible so long as the paper remained in control of the paper fingers. After the erasure has been made it is necessary to turn the platen backward and retract the paper so that writing may be resumed at the point where it stopped prior to the correction. Owing to the tendency of the sheets to "creep" or move relatively to each other during this back and forth feeding, they sometimes get out of register, causing an irregular spacing of the lines on the under sheet or sheets.

Moreover, in some of these prior constructions where no erasing surface either on the platen or elsewhere is conveniently disposed beyond the paper fingers, it is impracticable to advance the sheet for correction by turning the platen. In such a case when erasing is to be done it is necessary with paper fingers as heretofore constructed to move said paper fingers bodily away from each other toward the ends of the platen until they free the paper so that the outer sheet

or sheets may be turned back to expose the inner sheet or sheets. Then after the erasures have been made the paper fingers must be re-adjusted before the writing can be resumed.

The object of my present invention is to avoid the necessity of such forward and backward turnings of the platen and paper or such adjustment and re-adjustment of the paper fingers in making erasures or for other purposes; and this object I attain by providing a paper finger which may be moved away from the paper so as to free entirely the written part of the same, enabling it to be drawn back from the platen sheet by sheet to expose the characters last printed; and this without altering the points of connection between said paper fingers and their support.

To the above and other ends my invention consists in the features of construction, combinations of devices and arrangements of parts hereinafter described and particularly pointed out in the claims.

In the present instance the improved result is achieved by pivoting each paper finger or guide on its support in such a way that it may be swung laterally outward toward the adjacent end of the platen and away from the middle of the paper and then locked temporarily so that the operator may conveniently make erasures and manipulate the sheets. In my companion application Serial No. 499,376 filed June 1st, 1909, I achieve the result sought in another way, that is, by so constructing the paper finger support that said support and the paper finger or fingers thereon may be moved bodily away from the platen so as to leave entirely free the advance portions of the paper.

One form of my invention is illustrated in the accompanying drawings applied to a No. 10 Smith Premier typewriting machine but it is to be understood that the nature of the invention is such that it may be readily adapted to other styles of writing machines.

In the drawings, Figure 1 is a fragmentary front elevation of the platen and platen carrier of a No. 10 Smith Premier typewriting machine embodying my invention, parts of the machine being omitted and parts broken away. Fig. 2 is a top plan view of the platen and the paper finger supporting

rod, showing the paper fingers swung outward in abnormal position. Fig. 3 is a transverse vertical sectional view of the platen and platen carrier taken about centrally, the support of the platen carrier and a part of the top plate also being shown, parts being broken away. Figs. 4 and 5 are vertical sectional views taken transversely of the platen and showing one of the paper fingers in different abnormal positions, certain parts in Fig. 4 being broken away for the sake of clearness. Figs. 6, 7 and 8 are perspective views of details of my improved construction.

15 Referring first to Fig. 3 this shows the top plate 1 of the machine from which rise standards 2 (one of which is shown) supporting a grooved track-way 3. Anti-friction balls 4 coöperate with the grooves in the 20 track-way and with the angularly bent portions of a slide bar 5, said slide bar at its ends carrying end bars 6, the end bars and slide bar being comprised in the carriage truck. The platen carrier or frame comprises bars or rods 7 and 8 extending lengthwise of the platen and located respectively 25 above and below the same, said rods being connected by parallel end bars or pieces 9 and 10. Arms 11 extend rearward from the 30 end bars of the platen carrier and carry lateral studs 12 which engage in openings or seats in the carriage truck and on which as pivots the platen carrier may be tilted. Arranged in the platen carrier is a platen 13 35 from the ends whereof extend axle portions 14 which engage seats or depressions 15 formed in the end bars 6. The platen is or may be equipped with the usual or suitable feed rollers 16 and 17 arranged respectively 40 at the rear and front of the underside of the platen, said feed rollers being indicated by dotted lines in Figs. 3 to 5. A paper plate or scale 18 of the usual or suitable construction is arranged at the front of the platen 45 and below the printing line thereon, said plate extending lengthwise of the platen and being yieldingly supported. The usual or suitable paper table and paper apron or deflector (not shown) are provided.

50 The parts thus far described are not my invention and need not be set forth in greater detail.

The paper is introduced into the machine at the rear and fed over the paper table and 55 down behind the platen between the same and the feed roller 16, being guided by the paper deflector or apron forward to the roller 17 and thence upward between the platen and the paper plate or scale 18, after 60 which it is brought into coöperation with certain paper controlling and guiding devices usually termed paper fingers. Commonly two paper fingers are provided but one or four or any desired number may be 65 employed. The paper fingers may be and

preferably are mounted on the upper frame rod or bar 7 which serves as a support for said fingers. Each paper controlling and guiding device or paper finger contrivance comprises a carrier part or sleeve 19 which 70 surrounds and bears on the rod 7 and is slidable lengthwise thereof. The details of one of these sleeves, the sleeve of the right-hand paper finger in the present case, are shown in Fig. 7 which is a perspective view 75 from the rear. The sleeve is provided with a flange 20 which is formed with a rounded projection or lug 21, said lug engaging in a groove 22 formed in the lower rear side of the rod 7 and extending lengthwise throughout the same. The lug 21 prevents rotation of the sleeve on the rod 7 but permits endwise movement of the sleeve therealong. The flange 20 is formed at one end of the body portion by the sleeve and from the 80 other end of said body portion extends a portion 23 slightly less in diameter than the body portion and forming a shoulder at its junction therewith. The reduced portion 23 is formed with a longitudinally extending 85 slot 24 which registers with or opens into the groove or cut-out 22 in the rod 7. At its end opposite from the body portion 19 the portion 23 is further reduced as indicated at 25 to provide a seat for a flange 26. This 90 construction enables the paper finger proper and its carrier to be mounted on the sleeve between the flanges after which the flange 26 is driven on to its seat or otherwise secured 95 in place.

The reduced portion 23 of the carrier part or sleeve provides a bearing for a second carrier part which carries the paper finger proper. The last named carrier part is clearly shown in Fig. 6 and also appearing 100 in most of the other views, and is a block-like member comprising a hub portion 27 and a short extension 28 therefrom. The hub portion is formed with a bearing opening 29 and surrounds and bears on the reduced end 23 of the sleeve 19 and is held 105 from endwise movement thereon by the shoulder on the sleeve and by the flange 26. The hub 27 is cut away to provide a mouth or opening 30 into the bearing opening 29, said mouth being located just at the rear of the extension 28. Normally said extension projects at an angle upward and rearward from the rod 7 as shown in Fig. 3. The extension 28 is formed with a transverse opening which provides a bearing for a pivot pin 31 shown detached in Fig. 8. The pivot pin is provided with a head 32 and its end is reduced and squared as indicated at 33. The head 32 is oblong in shape, the two longer sides being straight and parallel. The pivot pin 31 enters its bearing opening in the extension 28 from the under side of said extension, and normally one of the longer sides of the head 32 is close to 110

115

120

125

130

and parallel with the mouth 30 of the opening 29, lying just outside said mouth. The thickness of the head 32 is slightly less than the width of the mouth 30 so that while normally the adjacent side of the head practically covers said mouth, yet when the pivot pin 31 is turned on its axis as presently to be described, one of the end portions of the head 32 is adapted to pass through the mouth 30 and into the opening 29. Normally, however, the pivot pin is prevented from being turned in this way by the face of the reduced sleeve portion 23 forward of the slot 24, as will be understood from a consideration of Fig. 3. The squared end portion 33 of the pivot pin 31 projects beyond the upper face of the extension 28 and carries an arm 35, said arm as shown in Fig. 2 being provided at its upper end with an inwardly extending rounded enlargement or head 36 which is formed with a square hole into which fits the squared end 33 of the pivot pin. A short headed screw 37 screws into a threaded opening in the squared end 33 so that the head 36 is confined between the head of the screw 37 and a shoulder formed at the junction of the squared portion 33 with the body of the pivot pin 31. The construction is such that the arm 35 and the paper finger proper carried thereby and presently to be described form practically one piece with the pivot pin 31. The pivot pin serves as an axle for the arm 35 enabling said arm and the paper finger proper to be turned or rotated under certain conditions on and independently of the rotary carrier part. From the inwardly off-set portion 36 the arm 35 is straight and inclines at an angle downward and forward over the top of the platen (Fig. 3), its lower end portion being curved or off-set inward toward the middle of the machine (Fig. 1) terminating in an enlargement or block 38. The enlargement is formed with a slot 39 which receives a pressure roll 40, said pressure roll being pivotally mounted in the sides of the slot. A knob or finger piece 41 is secured to the enlargement 38 and projects forward therefrom. A downward projection 42 on the enlargement 38 has secured to its under side as by rivets 43 the guiding portion proper of the paper finger which may be of sheet metal and comprises two guide fingers or extensions, one, 44, extending down over the paper scale 18, and the other, 45, extending inward toward the middle of the machine and slightly upward as best appears in Fig. 1.

The member comprising the extension 28 and the hub 27 is constantly tending to turn forward by reason of the pressure imparted to it by a wire spring 46 which is coiled around the body portion of the sleeve 19 and has one of its ends secured in a hole in the flange of said sleeve, the other end being

secured in a hole in the extension 28. The pressure of the spring 46 is transmitted from the extension 28 to the arm 35, roll 40 and fingers 44 and 45 tending constantly to press these parts toward the platen. The friction due to the spring 46 between the pressure roll 40 and the guide fingers 44 and 45 on the one hand and the platen or the paper thereon on the other hand, is sufficient to maintain the entire paper finger contrivance including the sleeve 19 in any position to which it may be adjusted lengthwise of the rod 7. When the knob 41 is pushed upward the paper fingers proper will be swung away from the platen, the extension 28 turning rearward to permit of this movement; and then the entire paper finger contrivance may be slid along the rod 7 and re-adjusted in any desired position.

As shown in the drawings there are two paper finger contrivances each constructed in the manner described above in detail and differing only in the respect that one is a right-hand contrivance and is off-set toward the left while the other is a left-hand contrivance and is off-set toward the right, the off-set portions of the two contrivances extending inward toward each other. Let it be assumed that the two contrivances have been properly adjusted to coöperate with the side portions or margins of the paper which is to be written on, and that a manifold packet of three sheets including an inner sheet *a*, a carbon inlay *b* and an outer sheet *c*, has been fed into the machine in the manner heretofore described. As the writing takes place and the sheets are advanced together line by line in the usual or any suitable manner, the leading end portions of the sheets will pass upward from the paper plate 10, the side margins of the sheets passing under the guide fingers 44 and 45 and the pressure roll 40 as well as under the lower inwardly curved or off-set portions of the arms 35. Thence the sheets advance between the straight portions of said arms 35 and back over the top of the rod 7, until said sheets are in the positions shown in Fig. 1. Suppose at this time it is desired to make an erasure. By means of the knobs 41 the paper fingers are swung upward from normal position shown in Figs. 1 and 3 to the position shown in Fig. 4. During this movement each paper finger proper and the associate arm 35 will swing together with the rotary carrier part on the reduced portion of the stationary carrier part or sleeve 23 as a bearing, the movement of the parts being in parallel planes transverse of the axis of the platen and of the supporting rod 7. As the paper fingers are swung upward a slight outward pressure toward the adjacent ends of the platen is maintained against each of the knobs 41. The movement of the paper fingers due to this outward pressure is re-

sisted initially by the surface of the sleeve portions 23 which serve as stops for the contiguous straight faces of the heads 32. When, however, the paper fingers have been 5 swung upward to the point where the heads 32 are in register with or opposite to the slots 24, as shown in Fig. 4, then the resistance to the turning of the heads 32 and connected parts is ended and the outward or 10 lateral pressure on the knobs 41 will cause the paper fingers to swing laterally outward toward the adjacent ends of the platen about the axes of the pins 31 as centers and in planes parallel with the axis of the platen, 15 the end portions of the heads 32 of said pins passing through the mouths 30 into and through the slots 24 and entering the groove 22 in the rod 7 as illustrated in Fig. 5. The lateral movements of the paper fingers will be limited by stop pins 47 projecting from the under faces of the extensions 20 28. Each stop 47 will be engaged by a portion of the associate head 32 at the opposite side of its axis from the portion which enters the groove 22. But the consequent arrest of the lateral movement of each paper finger takes place only after said paper fingers have been swung laterally outward entirely beyond the side edges of the paper to 25 30 the positions illustrated in Fig. 2. If, now, the operator releases the paper fingers they will be maintained in the Fig. 2 position by reason of the fact that though the springs 46 are tending to swing said paper fingers 35 forward about the axis of the rod 7 as a center, this tendency is resisted by the engagement of the head 32 with the upper sides of the groove 22 and the slots 24, the parts 22, 24 and 32 constituting locks or latches. 40 With the paper fingers in the positions shown in Figs. 2 and 5 it will be obvious that the portions of the sheets above the paper plate 18 are entirely free and that these portions may be separated and drawn forward singly, or two at a time as shown in 45 Fig. 5. With the sheets in the relation shown in said Fig. 5, the printing line on the under sheet *a*, which line is a short distance above and parallel with the upper edge of the paper or scale plate 18, will be exposed so that 50 an erasure may readily be made in the printing line, the platen serving as a backing. After such erasure the carbon inlay *b* may be turned upward and backward against 55 the sheet *a* and then a backing sheet may be inserted directly behind the outer sheet *c* so that the corresponding erasure may be made thereon. This being accomplished the 60 backing sheet may be withdrawn and the paper fingers may be restored to normal position. In practice, this may be accomplished by a slight inward pressure on each knob 41 sufficient to swing the paper fingers inward until the heads 32 disengage from 65 the grooves 22 and slots 24, after which the

springs 46 will operate to swing the paper fingers downward into contact with the paper and the writing may thereupon be resumed. When the paper finger contrivances are in normal position lateral movement of 70 each arm 35 in one direction is prevented by the co-action between the head 32 and the sleeve portion 23, while lateral movement in the opposite direction is prevented by the co-action between the head 32 and the pin 75 47. Moreover at all times the pins 47 co-operate with the heads 32 to prevent excess pivotal movement of the paper fingers inward toward each other.

By the operations above described the different sheets of a manifold packet or set may be freed for separate manipulation for the purpose of making erasures or for any other desired purpose without the necessity either of turning the platen forward and 80 backward and consequently advancing the paper forward and backward, or without moving the paper finger contrivances laterally to new positions with the consequent necessity of re-adjusting them in the old 85 positions after the erasures have been made.

It will be understood that though the motion of the paper fingers from normal position to the Fig. 2 position has been described in two steps, yet these steps are not 90 separated by an appreciable interval of time but merge one into the other so that the releasing and locking operation for each paper finger is practically a continuous one and occupies but an instant of time. It will further be understood that in the No. 10 Smith Premier typewriter it is desirable prior to 95 making erasures to tilt the platen and platen carrier upward and backward on the pins 12 as centers in order to raise the printing 100 line out of the way of certain of the carriage feeding and ribbon devices (not shown). This tilting operation is explained in detail in the application of Alexander T. Brown filed April 25th, 1906, Serial No. 110 313,603. In the present instance the tilting of the platen may be accomplished by pressure on one or both of the knobs 41 and follows the outward or lateral swinging of 115 the paper fingers to the Fig. 2 position. At the moment of arrest of the paper fingers by the engagement of the heads 32 with the stop pins 47 it will be apparent from a consideration of Fig. 2 that pressure against the knobs or finger pieces 41 is substantially rearward; and this rearward pressure after the lateral swing of the paper fingers has been arrested will operate to lift or tilt the platen. The result is that in such constructions as the present one, the throwing out 120 of the paper fingers and the tilting of the platen may be accomplished at what is really a single continuous operation.

The specific constructions of the guide fingers and the pressure rolls are not claimed 130

by me; but I believe that the means which enables the paper fingers to be moved away from the surface of the platen entirely out of the path in which the paper or work sheets are swung toward and away from the platen is new with me and I desire to claim it broadly as well as to claim the specific construction by which in the present instance the improved results are accomplished.

It will be observed by my present invention I combine with the platen a paper finger contrivance comprising a paper guide or guiding part or finger and means for enabling said part to be moved away from the surface of the platen entirely out of the path in which the portion of the paper that has passed the printing point may be drawn away from the platen so as to expose the printing point or the underlying sheets, the set position of the contrivance remaining unchanged; that in the present instance after the paper finger or fingers has or have been moved then the advanced portion or portions of the paper may be pulled away from the platen until arrested by the paper plate or scale; that in a front-strike typewriting machine like the present one the paper plate is arranged parallel with the printing line and below the same while the support or rod on which the paper finger contrivance or contrivances are mounted is arranged above the platen; that the paper guiding part or paper finger is pivotally mounted and may be swung on its pivot in planes parallel with the axis of the platen; that when two paper fingers are employed they may be swung laterally away from each other on their supports; that in the present instance in moving the paper fingers away from the platen they are first swung in paths or sets of planes which are parallel with each other and transverse of the platen axis, and are therefore after swung in planes at right angles with said parallel paths but parallel with the platen axis; that the movement of the paper fingers away from each other is also substantially lengthwise of the paper plate; that each of the paper finger contrivances in the present instance comprises a carrier and a paper guide or finger pivoted thereon; that the carrier is a two-part carrier, one of the parts being mounted to rotate on the other part which latter as here shown is a slidable sleeve; that the two carrier parts are connected by a spring; that the paper guide or finger is pivoted on the rotatable carrier part; that said paper guide is adapted to rotate with said rotatable part and also independently thereof; that normally said paper finger or guide is held positively from independent rotation on said rotatable carrier part; that means are

provided for locking the paper fingers in abnormal position; that said locking means are normally inoperative; that is, they cannot lock the paper fingers out owing to the fact that the locking parts are in normal relations such that coöperation between them can not take place for the purpose intended; and that as a prerequisite to rendering said locking means effective it is necessary to swing the paper finger in two directions at right angles to each other.

The term paper finger employed in the claims is used in its broadest sense and is to be construed as covering any paper controlling or guiding device for leading or directing the paper in a desired direction; and under this definition a roll would be included.

Various changes may be made without departing from the spirit and scope of my invention.

What I claim as new and desire to secure by Letters Patent, is:—

1. In a typewriting machine, the combination with the platen, of a paper finger contrivance comprising a support and a paper guide partly surrounding the platen and co-operative therewith at both sides of the printing line, said paper guide being pivoted on said support and inwardly off-set from its pivot toward the middle of the platen and said paper guide being movable independently of its support outwardly away from the middle of the platen and lengthwise of the platen.

2. In a typewriting machine, the combination with the platen, of a paper finger contrivance comprising a support and a paper guide partly surrounding the platen and co-operative therewith at both sides of the printing line, said paper guide being pivoted on said support and inwardly off-set from its pivot toward the middle of the platen and being movable independently of said support outwardly away from the middle of the platen and lengthwise thereof, and means normally preventing positive outward movement of said paper finger lengthwise of the platen.

3. In a front-strike typewriting machine, the combination with the platen and a paper plate extending lengthwise of the printing line below the same, of a paper finger contrivance comprising a guiding portion which is pivotally mounted above the printing line and which extends partly around the platen and across the printing line to guide the paper after it leaves said paper plate and also after it has passed the printing line, said paper guide being swingable on its support upward above the printing line and away from the surface of the platen and also outward laterally lengthwise of the platen and so as to free the side edge of the

paper, thereby enabling the paper to be pulled or drawn completely away from the platen surface to expose an underlying sheet.

4. In a front-strike typewriting machine, 5 the combination with a platen and a paper plate arranged parallel with the printing line and below the same, of a paper finger arranged at the front of the platen and set- 10 table lengthwise thereof and which coöper- ates with the paper after it leaves said paper plate, said paper finger comprising a guiding portion which coöperates with the platen to guide paper around the same, said guiding portion being movable upward and lat- 15 erally away from the paper plate to a position such that it stands outside a vertical plane passed through the adjacent edge of the paper, the set position of the paper finger remaining unchanged during this move- 20 ment of said guiding portion of said paper finger.

5. In a typewriting machine, the combination with a platen, of a pair of pivotally mounted paper fingers comprising supports 25 and inwardly off-set guiding fingers pivoted to said supports and which may be swung laterally away from each other.

6. In a typewriting machine, the combination with a platen, of a paper finger con- 30 trivance comprising a carrier and a paper guide thereon, said carrier being adjustable lengthwise of said platen to change the set position of said paper guide, and said guide being pivotally movable in two directions 35 at right angles to each other, the first pivotal movement being a necessary prerequisite to the pivotal movement at right angles thereto.

7. In a typewriting machine, the combination with a platen, of a paper finger con- 40 trivance comprising a support, a guide and a device connecting said support with said guide, said device being rotatable on said support, and said guide being rotatable on 45 said device.

8. In a typewriting machine, the combination with a platen, of a paper finger con- 50 trivance comprising a support, a guide and a device connecting said support with said guide, said device comprising a sleeve rota- 55 ble on said support and providing a bearing for said guide and on which said guide may be turned or rotated.

9. In a typewriting machine, the combination with a platen, of a paper finger con- 60 trivance comprising a support, a guide, a device connecting said support with said guide, said device comprising a sleeve rota- 65 ble on said support and providing a bearing for said guide on which said guide may be turned or rotated, and a spring connect- 70 ing said sleeve with said support.

10. In a typewriting machine, the combination with a platen, of a paper finger con-

trivance comprising a support, a guide, a de- 65 vice connecting said support with said guide, said device comprising a sleeve rotatable on said support and providing a bearing for said guide on which said guide may be turned or rotated, a spring connecting said 70 sleeve with said support, and a lock for holding said sleeve against rotation by said spring.

11. In a typewriting machine, the combination with a platen, of a paper finger con- 75 trivance comprising a two-part carrier, the carrier parts being relatively movable, and a guiding finger independently movable on one of said carrier parts.

12. In a typewriting machine, the combination with a platen, of a paper finger con- 80 trivance comprising a two-part carrier, a spring connecting said carrier parts, and a guiding finger pivoted on one of said parts and movable independently thereof. 85

13. In a typewriting machine, the combination with a platen, of a paper finger con- 90 trivance comprising a two-part carrier, one carrier part being rotatable on the other, a spring connecting said carrier parts and tending constantly to turn the rotatable part, and a guiding finger pivoted to swing on said rotatable part.

14. In a typewriting machine, the combination with a platen, of a paper finger con- 95 trivance comprising a two-part carrier, the carrier parts being relatively movable, and a guiding finger independently movable on one of said carrier parts, said movable carrier part being movable in planes transverse 100 of the platen axis and said guiding finger being independently movable in planes parallel with the platen axis.

15. In a typewriting machine, the combination with a platen, of a paper finger con- 105 trivance comprising a two-part carrier, one carrier part being rotatable on the other, a spring connecting said carrier parts and tending constantly to turn the rotatable part, and a guiding finger pivoted on said 110 rotatable part, said rotatable part being rotatable in planes transverse of the platen axis and said guiding finger being independently rotatable in planes parallel with said platen axis. 115

16. In a typewriting machine, the combination with a platen, of a paper finger con- 120 trivance comprising a two-part carrier, one carrier part being rotatable on the other, a spring connecting said carrier parts and tending constantly to turn the rotatable part, and a guiding finger pivoted on said ro- 125 tatable part, said rotatable part being rotatable together with said guiding finger in planes transverse of the axis of the platen and said guiding finger being rotatable alone and independently in planes parallel with the axis of the platen.

17. In a typewriting machine, the combination with a platen, of a paper controlling contrivance comprising a support, a guide, and mechanical connections between said support and said guide through which the guide is rotatable relatively to its support in planes transverse of the axis of the platen and also rotatable in planes parallel with the axis of the platen.
- 10 18. In a typewriting machine, the combination of a platen, a supporting rod extending lengthwise thereof, a sleeve adjustable along said rod, means for preventing rotation of said sleeve on said rod, a carrier part 15 rotatable on said sleeve, a spring coiled around said sleeve and having one end connected thereto and the other end connected to said carrier part, and a paper guiding finger pivoted on said carrier part.
- 20 19. In a typewriting machine the combination of a platen, a supporting rod extending lengthwise of said platen, said rod being formed with a longitudinal groove, a sleeve adjustable along said rod and provided with 25 a lug engaging said groove, a carrier part rotatably mounted on a reduced portion of said sleeve, a spring coiled around said sleeve and connecting said sleeve and said carrier part, and a guiding finger pivoted on 30 said carrier part.
20. In a typewriting machine, the combination with a platen, of a paper finger contrivance comprising a support, a paper guiding part, and connections between said support and said guiding part, which connections permit said guiding part to be given rotary motion in two different planes at right angles to each other.
- 40 21. In a typewriting machine, the combination with a platen, of a paper finger contrivance comprising a paper guiding part rotatable in planes at right angles to each other, said paper guiding part comprising an arm off-set inwardly toward the middle 45 of the platen and carrying a pressure roll and two angularly disposed guide fingers.
22. In a typewriting machine, the combination of a platen, a supporting rod extending lengthwise thereof, a sleeve adjustable along said rod, means for preventing rotation of said sleeve on said rod, a carrier part rotatable on said sleeve, a spring coiled around said sleeve and having one end connected thereto and the other end connected 55 to said carrier part, and a guiding part pivoted to said carrier part, said guiding part comprising an inwardly off-set arm carrying a pressure roll and two angularly disposed guide fingers.
- 60 23. In a typewriting machine, the combination of a platen, a paper finger contrivance adjustable to a set position and comprising a pivoted inwardly off-set guiding device extending crosswise of the printing
- line, and means for enabling the paper guiding device to be moved laterally to free the paper while the set position of said contrivance remains unchanged.
24. In a typewriting machine, the combination of a platen, a pair of paper fingers, a support common to both said paper fingers, means for affording movement of said paper fingers away from the surface of the platen and entirely out of the path in which the portion of the paper that has passed the printing point may be drawn away from the platen, the set position of the paper fingers remaining unaltered during such movement, and locking devices for each paper finger coöperative with said common support for holding said paper fingers in abnormal position, the locking devices for one paper finger operating independently of the locking devices for the other paper finger.
- 85 25. In a typewriting machine, the combination of a platen, a pair of paper fingers adjustable to different set positions to correspond with different widths of paper, said paper fingers having guiding portions normally spaced apart, when set for coöperation with a sheet of paper of a particular width, a distance less than the width of said paper, means for affording movement of said guiding portions to abnormal inoperative positions wherein said guiding portions are separated by a distance greater than the width of the paper although the set positions of said paper fingers remain the same as when said guiding portions were in normal position, and means for locking said guiding portions in abnormal positions.
- 90 26. In a typewriting machine, the combination with a platen, of a pivotally mounted paper finger which is inwardly off-set from its pivot and may be swung on its pivot in planes parallel with the axis of the platen to completely clear the adjacent side margin of the paper, and means for positively locking said paper finger in such abnormal position.
- 105 27. In a typewriting machine, the combination with a platen, of a pair of pivotally mounted paper fingers which may be swung laterally away from each other, and locking devices coöperative with said paper fingers positively to maintain them in the abnormal positions to which they may be swung, said locking devices operatively engaging during the lateral swinging movements of said 110 paper fingers.
- 120 28. In a typewriting machine, the combination with a platen, of a paper finger contrivance comprising a carrier and a paper guide pivoted on said carrier, said guide being rotatable on said carrier in planes parallel with the axis of the platen, and means for locking said guide in abnormal

position, said means operating during the rotatable movement of said guide as aforesaid.

29. In a typewriting machine, the combination with a platen, of a paper finger contrivance comprising a two-part carrier, the carrier parts being relatively movable, and a guiding finger independently movable on one of said carrier parts, and means for locking said guiding finger in abnormal position.

30. In a typewriting machine, the combination with a platen, of a paper finger contrivance comprising a two-part carrier, one part rotatable on the other, a spring connecting said carrier parts, a guiding finger pivoted on said rotatable part, and means for locking said guiding finger in abnormal position.

31. In a typewriting machine, the combination with a platen, of a paper finger rotatable in planes transverse to the axis of the platen and thereafter rotatable in planes parallel with the axis of the platen, and means for locking said paper finger in abnormal position after the second stage of its rotation.

32. In a typewriting machine, the combination of a platen, a laterally swinging paper finger, and a lock for said paper finger, said lock being normally inoperative but comprising parts which operatively engage during the lateral swinging movement of said paper finger.

33. In a typewriting machine, the combination with a platen, of a paper finger contrivance comprising a laterally swinging paper finger proper, and means for locking said paper finger in inoperative position, said means being normally inoperative but comprising parts which operatively engage during the lateral swinging movement of said paper finger.

34. In a typewriting machine, the combination with a platen, of a laterally swinging paper finger, means constantly pressing said paper finger toward the platen, and a normally inoperative lock, said paper finger being movable away from the surface of the platen and said lock thereafter automatically operating to maintain said paper finger in abnormal position.

35. In a typewriting machine, the combination with a platen, of a laterally swinging paper finger, means constantly pressing said paper finger toward the platen, a normally inoperative lock, and means for rendering said lock operative during the lateral swinging movement of said paper finger.

36. In a typewriting machine, the combination of a platen, a rod extending lengthwise of the platen and formed with a longitudinal groove, a sleeve slidable on said rod and having a part engaging in said groove, a spring-pressed carrier part rotatable on

said sleeve, said sleeve being formed with a slot opening into said groove and said carrier part being provided with a mouth or entrance way leading into its bearing opening, said mouth being normally out of register with said slot, and a paper guide pivoted on said carrier part and provided with a part movable through said mouth and engageable with said slot and with said groove.

37. In a typewriting machine, the combination with a platen, of a paper finger contrivance comprising a two-part support, one part being movable relatively to the other, a paper finger proper pivoted to swing laterally on the movable part of said support, and means for limiting the independent pivotal movement of said paper finger in both directions.

38. In a front-strike typewriting machine, the combination with a platen, of a normally operative paper finger contrivance comprising a guide, a support and connections between said guide and support which enable said guide to be moved upward and at the same time outward away from the surface of said platen in planes transverse of the platen axis and being thereafter movable in planes parallel with the platen axis.

39. In a typewriting machine, the combination with a platen, of a paper finger normally operative, said paper finger being movable away from the surface of said platen in planes transverse of the platen axis and being thereafter movable in planes parallel with the platen axis, and means for locking said paper finger in abnormal position after said second movement and prior to any return movement in the first named direction, said locking means being normally inoperative.

40. In a typewriting machine, the combination with a platen, of paper fingers adjustable toward and away from each other, said paper fingers each comprising a support, an inwardly off-set paper guiding portion, and connections between said guiding portion and said support, the guiding portions of said paper fingers being adapted to be swung away from the platen first in parallel paths and thereafter in planes at right angles to said parallel paths.

41. In a typewriting machine, the combination with a platen, of a pair of paper fingers adjustable toward and away from each other, said paper fingers having inwardly off-set paper guiding portions and being adapted to be swung away from the platen first in parallel paths and thereafter in planes at right angles to said parallel paths, and means for thereafter locking said paper fingers.

42. In a front-strike typewriting machine, the combination of a platen, a supporting rod extending lengthwise of the platen and above the same, a paper plate extending

longitudinally of the platen below the printing line, and a pair of paper finger contrivances mounted on said supporting rod and comprising inwardly off-set guiding portions, said paper fingers being adapted to coöperate with the paper after it leaves said paper plate and to guide the paper upward and backward over the top of said supporting rod, said guiding portions being independently movable laterally away from each other to inoperative positions.

43. In a front-strike typewriting machine, the combination of a platen, a supporting rod extending lengthwise of the platen and above the same, a paper plate extending longitudinally of the platen below the printing line, a pair of paper finger contrivances mounted on said supporting rod and comprising inwardly off-set guiding portions, said paper fingers being adapted to coöperate with the paper after it leaves said paper plate and to guide the paper upward and backward over the top of said supporting rod, said guiding portions being independently movable away from each other to inoperative positions, and means for locking said guiding portions in inoperative positions.

44. In a front-strike typewriting machine, the combination of a platen, a supporting rod extending lengthwise of the platen and above the same, a paper plate extending longitudinally of the platen below the printing line, and a pair of paper finger contrivances mounted on said supporting rod and comprising inwardly off-set guiding portions, said paper fingers being adapted to coöperate with the paper after it leaves said paper plate and to guide the paper upward

and backward over the top of said supporting rod, said guiding portions being independently movable to inoperative positions first in parallel paths transverse of the platen axis and thereafter in planes at right angles to said parallel paths.

45. In a typewriting machine, the combination of a carriage truck, a platen carrier supported on said truck, a platen on said platen carrier, said platen and said platen carrier being tiltable on said carriage truck, and a pair of paper finger contrivances on said platen carrier comprising independently movable paper guides and further comprising finger pieces by which said independently movable guides may each be moved in two sets of planes to inoperative position, said planes being at angles to each other and said finger pieces being thereafter operative to tilt said platen and platen carrier on said carriage truck.

46. In a typewriting machine, the combination of a platen, a support arranged over the platen, and a paper finger connected to said support, said paper finger being movable out of working position in two directions, one upwardly away from the platen and the other laterally longitudinally of the platen, and said paper finger maintaining its set position during its described movements out of working position.

Signed at Syracuse, in the county of Onondaga, and State of New York, this 24th day of May, A. D. 1909.

WILLIAM ALLAN DYER.
